SPECTACLE CASE

James T. Rakauskas, Chicago, Ill.

Application December 31, 1936, Serial No. 118,654

4 Claims. (Cl. 24-3)

My invention relates to spectacle cases, and more particularly to clips for attaching the same to a pocket, belt, dress fold or other garment, and my main object is to provide a clip which 5 has a simple connection with the spectacle case.

A further object of the invention is to so construct the novel clip, that no screws, rivets or other special fastening means are employed to secure it to the spectacle case.

10 A still further object of the invention is to design a spectacle case having an element for the retention thereon of the clip.

Another object of the invention is to combine 15 the clip and spectacle case in a manner to present a neat and inconspicuous appearance.

An important object of the invention is to make the connection of the clip to the spectacle case so economical to produce that no appreciable increase will result in the manufacturing cost of 20 the article.

With the above objects in view, and any others which may suggest themselves from the description to follow, a better understanding of the invention may be gained by reference to the accompanying drawing, in which—

Figure 1 is an elevation showing the improved spectacle case secured to a garment pocket;

Fig. 2 is an enlarged elevation of the improved spectacle case;

Fig. 3 is a more enlarged view of so much of the inner side of the spectacle case, as deals with the clip;

Fig. 4 is a vertical section in the zone of the clip, showing its application to the spectacle case cover; and

Fig. 5 is a view similar to Fig. 4, showing two steps in the securing of the clip to the said cover.

I have found that a clip attached to a spectacle case is a handy means to secure the same to the 40 pocket or other portion of a garment in order to prevent the dropping of the spectacle case to the floor when its owner takes a bending or stooping movement. A spectacle case so improved is shown in the prior patent art, but its 45 apparent absence from the market may be due to the fact that the method of attaching the clip is too costly or that the device is inefficient in use. I have therefore devised a spectacle case which eliminates these disadvantages.

50 In accordance with the foregoing, specific reference to the drawing shows a conventional spectacle case at 10 and its cover at 11. Spectacle cases are usually stamped from steel and are either embossed or wrapped with a fabric or leatherette covering.

The pocket clip 12 is applicable to the cover 11 as shown in Fig. 2, the shank 13 of the clip being slightly offset and passing through a horizontal slot 11a in the cover and extending upwardly behind the cover as shown in Figs. 3 and 5. In the novel embodiment I extend the spectacle case cover 11 with a tongue 11b in an upward direction and bend the same down inwardly, as shown in Figs. 3 and 5, to overlie the upper end of the clip shank 13. The tongue is then 10 made firm in a press, so as to permanently secure the clip to the spectacle case cover.

It will be understood that the above operation applies either to the plain or covered cases, as the case cover may be formed with the perforation 11a and the extended tongue 11b in either event. Also, when the clip has been secured as described, its shank will be designed to depart from the point fastened so as to extend in slightly spaced relation from the inner side of the case 20 cover. The clip being made of spring metal, it is seen that this expedient permits it to flex along its entire length when outwardly tensioned by the application of the clip to a pocket.

It is evident from the above description that 25 the improved spectacle case has an integral fastener for the clip, eliminating the need of screws, rivets or soldering. Further, the clip is rigidly secured only at its upper end so as to be free 30 to flex and move relative to the opening 11a when it is tensioned in an outward direction, being thus rendered more flexible and serviceable for a much longer period than a clip having only a portion flexible. Further, the improvement is ordinarily invisible from the outside so that only the clip is seen, the fastening or any suggestion thereof not being evident. Finally, it is easily apparent that the improvement enables 35 the spectacle case to be manufactured very economically for the application of the clip, so as not to appreciably increase the manufacturing cost due to the same.

I claim:—

1. A combined spectacle case and pocket clip 45 therefor, said case being formed to provide a substantially horizontal slot therein adjacent an upper edge portion thereon, an integral extension of said edge of said case above said slot, said clip including a shank extending through said 50 slot and upwardly towards said edge along the inside of said case, said extension engaging the free end of said shank and to fasten said clip to said case.

2. The structure of claim 1, said extension 55

overlying the free end of said shank and pressing the same against the inside of said case to accomplish its engagement with said shank.

3. A combined spectacle case and pocket clip therefor, said case being formed to provide a slot therein, an extension of said case adjacent said slot, said clip including a shank, said shank being extended through said slot with a portion thereof adjacent said extension, said extension being en-

gaged with said adjacent portion of said shank to attach said clip to said case.

4. A combined spectacle case and pocket clip therefor, said clip comprising a clip portion carried outwardly of said case and an integral shank carried inwardly of said case, an integral extension of said case, said extension being engaged with said shank to attach said clip to said case.

JAMES T. RAKAUSKAS.
